UNITED STATES PATENT OFFICE.

REYNOLDS C. FRAMPTON, OF SWISSVALE, PENNSYLVANIA, ASSIGNOR OF ONE-HALF TO JOHN P. REINECKE, OF PITTSBURG, PENNSYLVANIA, AND ONE-HALF TO PITTSBURG WATER HEATER COMPANY, OF ALLEGHENY, PENNSYLVANIA, A CORPORATION OF NEW JERSEY.

HEATER.

No. 867,357.

Specification of Letters Patent.

Patented Oct. 1, 1907.

Application filed November 19, 1906. Serial No. 343,977.

To whom it may concern:

Be it known that I, REYNOLDS C. FRAMPTON, a citizen of the United States, residing at Swissvale, in the county of Allegheny and State of Pennsylvania, have 5 invented certain new and useful Improvements in Heaters, of which the following is a specification.

This invention has reference to the provision of means in a heater—such for example, as the instantaneous water heater commonly employed in residences and 10 other places—whereby in case of a downdraft through the flue, the pilot light or other burning device will be protected from a blowout or disarrangement resulting from such downdraft, and whereby also the means for accomplishing the result referred to may be more compactly and inconspicuously installed and rendered 15 more efficient in operation.

A further object of this improvement is the provision of means which in its effect upon the draft or line of draft in heaters of the type specified will afford better 20 circulation of the heating gases than has been heretofore attained in ordinary constructions, whereby greater efficiency in the heating effect of the consumed gases is secured.

The above, as well as such other objects as may hereinafter appear, I attain by means of the construction illustrated in preferred form in the accompanying drawing, wherein—

Figure 1 is a side elevation of a heater embodying my improvement—a portion of the same being shown 30 as cut away or in section, and

Figure 2 is a sectional view on a larger scale, showing the details of my improvement.

Referring now more particularly to Figure 2, it will be seen that within the top cap or casting 3 of the heater 35 there is open space, in the center whereof is placed a peculiar double conical shaped block or deflector part marked 4 composed of an upper section 5 and a lower piece 6 held together by means of bolts 7 which also serve to support the cone through the instrumentality 40 of brackets 8 which are secured to the walls of the cap of the heater by bolts 9 or other suitable securing devices.

As a means for directing the currents of the consumed gases I may employ, if desired, a deflecting plate 10 45 which will operate in conjunction with the cone 4 in a manner to be hereinafter more particularly described, and around the base of the cap part 3 I arrange a plurality of egress openings 11 of sufficient capacity to answer the required purpose, which is to allow the outflow of air or gas or products of combustion which may result 50 from a downdraft from the chimney or flue to escape after it passes the part 5 of the central cone member when such downdraft occurs.

It will be observed that the particular arrangement of the plate 10 aids in forcing the currents as they come 55 downward to pass out through the openings 11 instead of passing down through the center of the heater and blowing out or disarranging the pilot flame 13 or other blaze. While the deflector plate 10 will materially aid in such operation, it is also evident that by virtue of the peculiar shape of the passage between the upper surfaces of the cone 4 and the cap or hood any downdraft will be directed outward through the openings 11, also, so at least some of the advantages of my invention could be attained without the use of the deflector 60 plate 10.

It will be observed that upward draft will pass around the deflector plate 10 and around the cone and out through the flue. In practice I make the sum of the areas of the openings 11 slightly in excess of the area 70 of the main flue.

Another advantage of my improvement is that it causes a better circulation of the gases in the upward flow of the products of combustion than where there is no central cone employed, as the presence of the cone 75 causes the gas to come into more intimate contact with the coils, that is those of larger circumference.

Still another advantage of the arrangement in question—particularly with reference to the row of openings 11 around the cap—is that where there is a condition of stagnation in the flue, as in cases where the interior of the flue has not been heated and the gases are not passing upward, if there is a sudden increase in the blaze or fire in the heater as occurs where the flow of gas is controlled by some automatic device indicated diagrammatically at 14, there may be some circulation by the outflow through the openings 11 until the amount of heat which works up through the flue starts a draft and causes the heater to draw in that direction.

Having thus described my invention and illustrated 90 its use, what I claim as new and desire to secure by Letters Patent, is the following:

1. The combination with a heater cap or hood provided with outwardly directed openings, of a deflector supported in the hood adjacent the openings and shaped to deflect 95 downward draft outwardly through the openings.

2. The combination with a heater cap or hood provided with outwardly directed openings, of a deflector supported in the hood with its lower edges adjacent the openings, and having upwardly converging sides.

3. The combination with a heater cap or hood provided with outwardly directed openings, and with a laterally extending plate below the openings, of a deflector supported in the hood adjacent the openings and shaped to deflect downward draft outwardly through the openings.

4. The combination with a heater cap or hood provided with outwardly directed openings, and with a laterally extending plate with its inner edge upwardly directed, of

a deflector supported in the hood adjacent the openings and shaped to deflect downward draft outwardly through the openings.

5. In a heater cap or hood provided with outwardly directed openings, of a deflector therein comprising a double cone with one apex extending upwardly and the other extending downwardly, the cone being located opposite the openings.

6. The combination with a heater cap or hood, provided

10 with outwardly directed openings and with a laterally

extending plate below the openings, of a deflector supported in the hood adjacent the openings, and comprising a double cone with one apex extending upwardly and the other downwardly.

In testimony whereof I have hereunto signed my name 15 in the presence of the two subscribed witnesses.

REYNOLDS C. FRAMPTON.
